UNITED STATES PATENT OFFICE.

THOMAS L. LEE, OF ROCHESTER, NEW YORK, ASSIGNOR TO NORTH EAST ELECTRIC COMPANY, OF ROCHESTER, NEW YORK, A CORPORATION OF NEW YORK.

COMBINED IGNITION COIL AND SWITCH.

Application filed June 9, 1927. Serial No. 197,735.

In order to render difficult the theft of a motor vehicle, it is customary to control the ignition circuit or circuits of the vehicle by means of a switch which is normally locked, and which can be operated only by the use of a suitable key. Where the switch and the ignition coil are made as separate units, connected by intermediate wires, it is an easy matter to circumvent this precaution by making a temporary connection around the switch. Accordingly, it has been proposed to enclose the switch, the coil and the wires connecting them within a metal housing or enclosure of some kind, which will render difficult the necessary access to the terminals of the switch and the coil.

The present invention relates to a combined switch and ignition coil, constructed and arranged in the general manner just referred to, and the purpose of the invention is to produce a structure which shall be simple, compact, efficient and inexpensive.

To the foregoing end the invention consists in the combined ignition coil and switch illustrated in the accompanying drawings and hereinafter particularly described, as it is defined in the claims which form a part of this specification.

In the accompanying drawings Fig. 1 is a front elevation of a combined switch and ignition coil embodying the present invention. Fig. 2 is a partly sectional side elevation of the same, and Fig. 3 is a side elevation showing the combined structure as it is mounted upon the dash or instrument board of a motor vehicle.

The invention is illustrated as embodied in a structure in which the ignition coil comprises windings 5 placed upon a core member 6, the latter having a generally rectangular form. The coil is enclosed between front and rear housing members 7 and 8, respectively, these members having side-flanges which rest against opposite sides of the core member 6. Rivets 9 pass through the flanges and the core member and thus secure these parts permanently together. A high-tension terminal member 10 is shown as mounted in the front housing member.

The front housing member 7 is embodied in a casting which also provides a support for the ignition switch, having for this purpose a downward extension 11 with a flat rear surface. The switch comprises a base

member 12 of insulating material, in which suitable terminals 13 are embedded, this base being fixed to the face of the support 11. Cooperating with the switch base is a rotatable switch member, comprising a spring-pressed contactor 14 which is brought into and out of engagement with the switch terminals by rotary movement, in a well-known manner. The contactor is connected with the rotatable barrel of a lock 15, and the contactor and the lock are supported, in proper relation with the switch base, by a housing 16. This housing entirely encloses the switch members and is attached to the switch support 11 by means of screws 17. To provide space for concealed connections between the coil and the switch, the housing member 7 is provided with a forwardly recessed portion 18, and the primary winding of the coil, as indicated in broken lines in Fig. 2, is connected with the appropriate switch terminals by wires 19 which extend through the recess so provided.

The combined coil and switch is designed to be mounted at the front or concealed surface of the dash or instrument board 20 of a vehicle, with the lock extending through and accessible from the rear or exposed face of the dash or instrument board, as shown in Fig. 3. For this purpose the front housing member 7 is provided with three perforated lugs 21, adapted to receive screw-bolts 22, which secure the coil and switch in place. Sleeves 23, surrounding the bolts, may be used to space the coil properly from the supporting surface.

It will be seen that the structure just described encloses the switch terminals and its connections with the coil entirely within metal members, which cannot be readily separated unless the structure has first been removed entirely from the dash or instrument board, and, as this last operation involves substantial expenditure of time, the arrangement affords security against unauthorized operation of the ignition apparatus.

The invention claimed is:

1. In a combined switch and ignition coil, the combination of a coil, front and rear housing members embracing the coil, the rear housing member having an extension beyond the front member, a switch base seated on the front of said extension, a movable switch member cooperating with the

switch base, a separable switch housing fixed to the front of said extension, enclosing the switch members and having a forwardly open end to receive a lock by which the 5 switch may be actuated, and connections, between the switch and the coil, enclosed and concealed with the rear housing member and the switch housing.

2. In a combined switch and ignition coil, 10 the combination of a coil provided with a magnetic yoke, a housing member supporting the coil, enclosing the rear side thereof and secured to said yoke, said member hav-

ing a projection beyond the yoke at one end, a switch housing mounted on the front of 15 said projection, a switch enclosed within the switch housing and having insulated terminals projecting through said projection and accessible at the rear thereof, and connections, between the switch and the coil, 20 enclosed and concealed within said housing member and the switch housing, the latter being open at the front to receive a lock by which the switch may be actuated.

THOMAS L. LEE.
